UNITED STATES PATENT OFFICE

HERBERT G. WHITEHOUSE, OF NEWARK, NEW JERSEY, ASSIGNOR TO THE RIKER COMPANY, A CORPORATION OF NEW JERSEY

BUCKLE FASTENER

Application filed April 15, 1932. Serial No. 605,387.

This invention relates to fasteners; and the invention has reference, more particularly, to a novel buckle fastener especially adapted for use in connecting shoe straps and the like.

8 Buckle fasteners, as heretofore constructed, usually have one piece frames, which, when attached to a shoe strap, lie snugly against the strap, thereby making it difficult to pass the cooperating shoe strap through the buckle 10 as when fastening or unfastening the straps. Also, when the cooperating shoe strap is in fastened position within the buckle, the latter oftentimes tends to bulge such strap outwardly in the region of the tongue-bar of the 15 buckle, thereby presenting an unattractive appearance as well as tending to exert undue pressure upon that portion of the foot of the wearer underlying the buckle.

20 The principal object of the present invention is to provide a novel buckle fastener which is so constructed as to enable the easy passage of a strap therethrough as when fastening or unfastening such strap, the said buckle fastener having an anchor frame, a 25 buckle frame and a keeper frame, the said buckle and keeper frames being designed to be turned outwardly with respect to the anchor frame in use, whereby ready access is had to the buckle and keeper frames.

30 Another object of the present invention lies in the provision of a novel buckle fastener of the above character which is simple and economical to manufacture and which is effective and durable in use, the same being 35 comfortable to the wearer and extremely attractive in appearance.

Other objects of this invention, not at this time more particularly enumerated, will be 40 clearly understood from the following detailed description of the same.

The invention is clearly illustrated in the accompanying drawing, in which:—

45 Fig. 1 is a fragmentary plan view illustrating the novel buckle fastener of the present invention applied to shoe straps.

Fig. 2 is a view in elevation of the structure shown in Fig. 1.

50 Fig. 3 is a sectional view taken along line 3—3 of Fig. 1 and also illustrates by dotted

lines, the manner of threading a strap through the buckle fastener.

Fig. 4 is a plan view of a portion of the structure shown in Fig. 1, the instep strap being removed from the buckle fastener. 55

Fig. 5 is a view similar to Fig. 2 but of a slightly modified form of construction; and

Fig. 6 is a plan view of a portion of the structure shown in Fig. 5, the instep strap being shown removed from the buckle fastener. 60

Similar characters of reference are employed in all of the above described views to indicate corresponding parts.

Referring now to the said drawing, the 65 novel buckle fastener of this invention is illustrated as used to secure the straps of a lady's shoe across the instep, but the same may be employed separably to connect straps or tapes for other purposes, and this invention is not intended to be limited to the precise construction of the use herein described, except as the invention may be defined in the appended claims. 70

In Figs. 1 to 4 there is shown one form of 75 the novel buckle fastener of this invention, which buckle fastener comprises an anchor frame 4 adapted to be secured as by stitching 5 to the stub strap 6 on one side of the upper of a lady's slipper (not shown). The 80 anchor frame 4 is illustrated as of substantially rectangular shape in plan, although the same may have various shapes, and is provided with hinge knuckles 7 and 8 at its ends. The end portion of the anchor frame 4 having the hinge knuckles 7 is bifurcated for receiving the buckle tongue 9 within the bifurcation thereof. The buckle tongue 9 is pivotally mounted on the buckle frame 10 intermediate the hinge knuckles 7. The buckle 85 frame 10 extends through and is pivotally mounted within the hinge knuckles 7 of anchor frame 4. 90

A keeper frame 11 is pivotally mounted within the hinge knuckle 8 of anchor frame 4. 95 The buckle frame 10 as well as the keeper frame 11 are illustrated as of substantially oval shape in plan, but it will be apparent that these two frames may have various shapes, such as square, rectangular or any 100

other desired configuration. The instep strap 12 has perforations 13 therein and is adapted to be passed through buckle frame 10 so that buckle tongue 9 may be engaged in one of the perforations 13. After the tongue 9 is thus engaged, the free end portion of strap 12 is adapted to be passed through the keeper frame 11.

Owing to the hinged connection of the buckle frame 10 with the anchor frame 4, this buckle frame may be turned upwardly, as illustrated in dotted lines in Fig. 3, when it is desired to either insert the strap 12 through the buckle frame 10 as when fastening the straps 6 and 12 together; or when removing the strap 12 from the buckle frame as when unfastening these straps. Likewise, the keeper frame 11 may be turned upwardly to enable the easy passage of the instep strap 12 therethrough, as is also shown in Fig. 3. The use of the anchor frame 4, not only enables the buckle frame and keeper frame to be pivotally mounted, but also spaces these frames apart sufficiently so as to enable easy access to either one or the other of these pivoted frames without interference from the other. With the instep strap 12 passed through the buckle fastener and secured, as shown in Fig. 1, the same presents a very attractive appearance and eliminates any excessive bulging of the instep strap outwardly.

In the form of the invention shown in Figs. 5 and 6, the anchor frame 14 is illustrated as of hollow rectangular shape and is formed with an intermediate tongue-bar 15 for pivotally receiving the buckle tongue 16 which cooperates with the buckle frame 17. The buckle frame 17 is formed with bent over hinge knuckles 18 which, by encircling one end of anchor frame 14, serve to pivotally connect this buckle frame to the anchor frame 14. The keeper frame 19 is also provided with bent over hinge knuckles 20 for pivotally connecting this keeper frame to the other end of the anchor frame 14. Stitching 21 is adapted to secure the buckle frame 14 to stub strap 22. In this form of the invention as in Figs. 1 to 4, the buckle frame 17 and the keeper frame 19 are adapted to be turned upwardly to enable the easy insertion or removal of the instep strap 23.

As many changes could be made in the above construction and many apparently widely different embodiments of this invention could be made without departing from the scope thereof, as defined by the following claims, it is intended that all matter contained in the above description or shown in the accompanying drawing shall be interpreted as illustrative and not in a limiting sense.

What is claimed is:

1. A buckle fastener of the class described comprising, an anchor member adapted to be attached to a strap or other support, said

anchor member having hinge knuckles at its ends, one end portion of said anchor member being bifurcated for receiving a buckle tongue therewithin, a buckle frame hingedly connected to the hinge knuckles at the bifurcated end of said anchor member, said buckle frame having a buckle tongue pivotally mounted thereon intermediate the hinge knuckles of said anchor member, a keeper frame hingedly connected to the hinge knuckle at the other end of said anchor member, said buckle frame and said keeper frame being turnable outwardly about their hinged connections with said anchor member and away from said strap to enable a cooperating strap to be readily passed through said buckle and keeper frames as when fastening or unfastening said straps.

2. A buckle fastener of the class described comprising, an anchor member adapted to be attached to a strap or other support, a buckle frame hingedly connected to one end of said anchor member and a keeper frame hingedly connected to the other end of said anchor member, a buckle tongue pivoted upon said anchor member and cooperating with said buckle frame for attaching a second strap to said first named strap, said buckle frame and said keeper frame being turnable outwardly about their hinged connections with said anchor member and away from said first named strap, thereby enabling said second strap to be readily passed through said buckle and keeper frames as when fastening or unfastening said straps.

3. A buckle fastener of the class described comprising, an anchor frame member adapted to be attached as by sewing to a strap or other support, said anchor frame member being of hollow rectangular shape and having a tongue-bar intermediate the length thereof, a buckle frame hingedly connected to one end of said anchor frame member and a keeper frame hingedly connected to the other end of said anchor frame member, a buckle tongue pivoted upon the tongue-bar of said anchor frame member and cooperating with said buckle frame for attaching a second strap to said first named strap, said buckle frame and said keeper frame being turnable outwardly about their hinged connections with said anchor frame member and away from said first named strap, thereby enabling said second strap to be readily passed through said buckle and keeper frames as when fastening or unfastening said straps.

In testimony, that I claim the invention set forth above I have hereunto set my hand this 9th day of April, 1932.

HERBERT G. WHITEHOUSE.
